DUAL MAGNETIC TAPE-CONSOLE UNIT FOR AN ELECTRONIC TYPING SYSTEM

Robert A. Clowe, Penfield, N.Y., assignor to
Xerox Corporation, Stamford, Conn.

Filed Nov. 22, 1974, Ser. No. 526,295

Term of patent 14 years

Int. Cl. D14—02

U.S. Cl. D26—5 C

FIG. 1

FIG. 2

FIG. 3

FIG. 4

FIG. 5

FIG. 6

FIG. 1 is a right front perspective view of a dual magnetic tape-console unit for an electronic typing system showing my new design;

FIG. 2 is a front elevational view thereof;

FIG. 3 is a rear elevational view thereof;

FIG. 4 is a top plan view thereof;

FIG. 5 is a left side elevational view thereof; and

FIG. 6 is a right side elevational view thereof.

I claim:

The ornamental design for a dual magnetic tape-console unit for an electronic typing system, as shown.
